A. B. FOWLER.
APPARATUS FOR REMOVING DUST.
APPLICATION FILED SEPT. 21, 1917.

1,402,755.

Patented Jan. 10, 1922.

INVENTOR
Alfred B. Fowler

UNITED STATES PATENT OFFICE.

ALFRED B. FOWLER, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

APPARATUS FOR REMOVING DUST.

1,402,755.

Specification of Letters Patent. Patented Jan. 10, 1922.

Application filed September 21, 1917. Serial No. 192,502.

To all whom it may concern:

Be it known that I, ALFRED B. FOWLER, a citizen of the United States, residing at Beverly, in the county of Essex and State 5 of Massachusetts, have invented certain Improvements in Apparatus for Removing Dust, of which the following description, in connection with the accompanying drawings, is a specification, like reference characters 10 on the drawings indicating like parts in the several figures.

This invention relates to abrading machines and is herein illustrated as embodied in a machine for buffing the bottoms of boots 15 and shoes.

In buffing the bottoms of boots and shoes a large amount of dust is generated, for the removal of which dust-hoods of various constructions have been provided but thus far 20 without satisfactory results. In the buffing operation the shoe is held against the lower forward portion of the buffing roll, the bulk of the dust being thrown off by the roll in a generally backward direction while the re- 25 mainder is carried around the roll after the manner of an atmosphere. The hoods which have been commonly used hitherto have to an extent carried away the dust which is thrown off by the roll but have been ineffec- 30 tive to carry away that which is carried around by it.

The general object of the present invention is to provide means for breaking up and carrying away the film or envelope of dust 35 bearing atmosphere which is carried around by the roll, as well as to provide improved means for carrying away the dust which is centrifugally thrown off by the roll.

A feature of the invention comprises 40 means for applying a concentrated draft to the tool to break up and draw away the film of dust bearing atmosphere carried around by the tool during the buffing operation. Preferably this means comprises a partition 45 or diaphragm concentric with the tool, located close to its rear surface and provided with suction ports of small cross-section. The suction is thus concentrated at these 50 points so that the pressure of the outside atmosphere, and centrifugal force, will cause the film of dust-bearing air which envelops

and is carried around by the roll to be broken up and removed through the ports 33.

This and other features of the invention, including certain details of construction and 55 combinations of parts, will be described as embodied in an illustrative machine and pointed out in the appended claims.

Referring to the accompanying drawings, 60

Fig. 1 is a perspective view of the head of a buffering machine in which the present invention is embodied;

Fig. 2 is a cross-section through the dust-hood and one of the buffering rolls, a shoe being shown in dotted lines in position to be 65 buffed;

Fig. 3 is a cross-section similar to Fig. 2, but showing the cover raised and the diaphragm moved away from the roll to facilitate the removing and replacing of the abrasive cover of the roll, and 70

Fig. 4 is a perspective of the diaphragm.

Mounted in bearings in the frame of the machine is the usual shaft 5 having at one 75 end a pulley 7 by which it may be driven. The buffering rolls 9, one having a coarse, and the other a fine sandpaper cover are mounted upon the shaft in the usual manner, said rolls being of the common split type comprising two half-cylinders hinged together 80 and adapted to be opened and closed when the sandpaper covers are removed and replaced. The hood 11, which has the usual outlet 13 adapted to be connected to any suitable suction device, has a lower wall 15 which extends into proximity to the lower part of the rolls and an upper wall 19 upon which the cover 21 is mounted. This cover has formed upon or fast to its ends bell crank 85 levers 23 having trunnions 25 which are rotatable in lugs 27 formed on the upper wall of the hood. It is evident that when the levers are swung back, as illustrated in Fig. 3, the cover will be raised. Normally, however, the cover lies close to the top of the roll 90 as shown in Figs. 1 and 2.

As has been stated, the shoe is presented to the roll in the position indicated in Fig. 2. The dust is generated at the point of contact and a large part of it is thrown off 100 tangentially. The edge of the lower wall 15

of the hood should be somewhat below this point in order to carry away this dust, but if it is located properly for this purpose the opening between it and the roll is so great that the force of the suction is liable to be dissipated owing to the size of the opening as compared to that of the outlet pipe 13. If the force of the suction available were unlimited this difficulty would not 10 present itself, but the force available in the ordinary shoe factory is always quite limited and must be conserved or concentrated to be efficient. For the purpose of narrowing the effective area of the mouth of the hood, as 15 well as for another purpose presently to be described, a partition or diaphragm 29 located close to the rear of the rolls has its lower edge extending down into proximity to the edge of the lower wall 15 of the hood 20 so as to provide a restricted opening or mouth which concentrates the draft at this point and removes the dust which is thrown off by the rotating roll.

Said lower edge is also close to the roll 25 and it therefore serves to divide the inflowing current of air so that the portion of air which flows between the diaphragm and the tool forms another concentrated draft which is carried around between the roll and the 30 diaphragm and unless removed would finally deposit particles on the bottom of the shoe. In order to prevent this undesirable occurrence the diaphragm is provided with suction ports 33 in the form of slots of small 35 cross-section through each of which is applied a concentrated draft to the rear of the roll to break up the atmosphere of dust and draw it away. The sum of the areas of the cross-sections of the mouth and of the ports 40 33 should be not greater than the area of the cross-section of the outlet pipe 13. Preferably it should be less; but whatever the exact relation, the draft should be strong at the points mentioned, and particularly at 45 the ports 33 where the rotation of the roll is acting to carry the dust out of the hood.

In order to facilitate the removal of the sandpaper cover of the roll and its replacement by a fresh one, the diaphragm 29 is arranged to be moved back away from the roll 50 when desired. To this end tails 35 formed integral with the diaphragm are provided with slots 39 and pins 47. The slots 39 receive pins 41 carried by the end walls of the hood, and the pins 47 pass through slots 55 formed in said walls. Levers 43 pivoted at their middle portions to said end walls have yokes at both ends, the upper yokes engaging eccentric pins 45 on the hubs of the bell 60 crank levers 23, and the lower yokes 37 engaging the pins 47 on the tails 35 of the diaphragm. When, therefore, the bell crank levers 23 are moved into the position shown in Fig. 3, the cover 21 is swung back and the 65 diaphragm moved back away from the roll

so that the sandpaper cover of the roll may readily be removed and replaced.

Although the invention has been set forth as embodied in a particular machine, it should be understood that the invention is not limited in the scope of its application to the particular machine which has been shown and described.

Having thus described my invention, what I claim as new and desire to secure by Letters Patent of the United States is:—

1. A machine of the class described having, in combination, a dust-hood through which air is drawn to remove the dust generated by an abrading operation, a rotary abrading tool partially closing the open end of the hood, one wall of the hood terminating in a portion spaced from the periphery of the tool to form an ingress opening, and a diaphragm curved closely about the periphery of the tool and terminating at the ingress opening to divide the draft and confine a portion thereof on the periphery of the tool to draw away the atmosphere carried around by the tool during its rotation. 90

2. A machine of the class described having, in combination, a dust-hood through which air is drawn to remove the dust generated by an abrading operation, a rotary abrading tool partially closing the open end 95 of the hood, one wall of the hood terminating in a portion spaced from the periphery of the tool to form a main suction opening for abrasive particles and air, and means to decrease the main suction opening and to 100 confine a portion of the draft close to the periphery of the tool to draw away the atmosphere carried around by the tool during its rotation.

3. A machine of the class described having, in combination, a dust-hood through which air is drawn to remove the dust generated by an abrading operation, a rotary abrading tool partially closing the open end of the hood, one wall of the hood terminating in a portion spaced from the periphery of the tool to form an ingress opening for abrasive particles and air, and a curved diaphragm within the hood and conforming closely to the periphery of the tool and terminating near the ingress opening, the diaphragm constructed with a suction port of small cross section opposite the periphery of the tool to draw off the atmosphere carried around by the tool during its rotation. 115 120

4. A machine of the class described having, in combination, a rotary abrading tool, a dust-hood through which air is drawn to remove the dust generated by the abrading operation, said hood having a cover located close to the top of the tool, a diaphragm located close to the rear of the tool, said diaphragm being provided with a suction port of small cross-section to remove the dust carried around by the tool during its 125 130

rotation, and means for moving the cover and the diaphragm away from the tool in different directions.

5. A machine of the class described, having in combination, a rotary abrading tool, a dust hood, said hood having a cover located close to the top of the tool, a diaphragm located close to the rear of the tool,

and means connecting the cover and the diaphragm constructed and arranged to move the diaphragm away from the tool in a different direction from the cover when the cover is raised.

In testimony whereof I have signed my name to this specification.

ALFRED B. FOWLER.
